UNITED STATES PATENT OFFICE.

GUY F. HOOVER, OF SHERMAN, TEXAS.

RECORDING DEVICE.

1,029,062.

Specification of Letters Patent.

Patented June 11, 1912.

Application filed July 22, 1911. Serial No. 640,000.

To all whom it may concern:

Be it known that I, GUY F. HOOVER, a citizen of the United States, residing at Sherman, in the county of Grayson and State of Texas, have invented certain new and useful Improvements in Recording Devices, of which the following is a specification, reference being had to the accompanying drawings.

10 This invention relates to recording and indicating devices for grain mills and more particularly to certain improvements in devices of that character shown and described in my prior application for patent filed 15 April 4th, 1911, Serial Number 318,877.

The present invention has for its primary object the provision of improved means for accurately recording and indicating the weight of a continuously flowing stream of 20 material and for indicating the number of pounds producing a barrel of flour irrespective of the grade of such material.

Another object of the invention is to provide improved means for mounting and actuating the indicator arms whereby the weight of the flour and of the feed are simultaneously recorded.

Still another object of the invention is to provide a device of the above character which is of comparatively simple construction and which is so arranged and mounted that absolutely accurate results are assured.

With the above and other objects in view, 35 the invention consists of the novel features of construction, combination and arrangement of parts hereinafter fully described and claimed, and illustrated in the accompanying drawings, in which—

40 Figure 1 is a front elevation of a machine embodying my improvements; Fig. 2 is a side elevation, the cylinder casing being shown in section; Fig. 3 is an enlarged detail section taken on the line 3—3 of Fig. 2; Fig. 4 is a detail section taken on the line 4—4 of Fig. 1; Fig. 5 is a detail perspective view of the jointed pencil carrying member and portions of the intermediate indicator rods to which said member is connected; Fig. 6 is an enlarged vertical section taken 50 on the line 6—6 of Fig. 1; Fig. 7 is a detail perspective view of one of the indicator arms; and Fig. 8 is a detail section taken on the line 8—8 of Fig. 2.

55 In my prior application, hereinbefore referred to, there is shown a counter-balanced

shaft having a material receiving cylinder arranged on one end, and means to be actuated when the cylinder is overbalanced by the weight of the material to indicate the weight of such material. These broad features of construction are retained in the present application, wherein the specific improvement resides in the provision of means whereby the weight of the material passing through the machine is not only indicated but also permanently recorded.

Referring now more particularly to the accompanying drawings 5 designates a suitable frame structure which is centrally divided by a vertical wall 6. A horizontal beam 7 extends through this wall and is supported at its ends by the uprights 8 which are secured to the ends of the frame. To the beam 7 and upon each side of the wall 6, a pair of depending hanger rods 9 are rigidly secured. In the lower ends of these rods a longitudinally disposed pivot shaft 10 is mounted. This shaft extends through a tubular hub or sleeve 11. To the sleeve 11 the coupling members 12 are secured. These members extend at right angles to the pivot shaft 10 and are of T-shaped form. To the central depending extensions of said coupling members the similar members 13 are connected, said latter members providing bearings or supports for the cylinder shaft 14. To one of the members 12, a rod 15 is connected and the other of said members carries an attaching plate 16 which is rigidly bolted or otherwise secured to the case 18 of the cylinder 17 which is rigidly fixed upon one end of the shaft 14. To the rod 15 a counter-balancing weight 19 is secured, said weight normally equalizing the weight of the cylinder 17 so as to maintain the rod 95 and the cylinder shaft in a horizontal plane. The cylinder casing 18 is provided at its top with an upwardly extending tapered inlet neck 20 in which the lower end of a flexible conducting tube 21 is disposed. The upper end of this tube is fixed to the top of the frame 5 beneath the hopper 22 into which the chute 23 deposits the material. The end of the rod 15 adjacent to the weight 19 is connected to a suitable dash pot 24 which prevents any unsteady movement of the parts and absorbs all shock or jar thereto when the receiving cylinder returns to its normal position.

Upon the cylinder shaft 14 and between 110

the members 13 a sprocket wheel 25 is secured, and this sprocket wheel is traversed by an endless chain 26 which passes around a similar sprocket on the drive shaft 27 which extends through the lower end of the frame structure.

It will be understood that the foregoing description of parts which relates to the mounting of the material receiving cylinder 10 and the manner in which the same is balanced, is precisely the same upon each side of the central vertical wall 6 of the frame, and that such arrangement may be still further multiplied if desired.

15 Particular attention is called to the fact that the point of connection of the power transmission chain 26 to the cylinder shaft is directly below the pivot shaft 10 whereby the cylinder and its case are supported.

20 I will now proceed with the description of the manner in which an accurate determination and record of the amount of material passing through the machine and also the number of pounds to each barrel of

25 flour milled, is obtained.

With the above objects in view, I provide the inwardly extending rods 28 which are secured to the rods 15. The rods 28 each carry a pair of vertically disposed bolts 29.

30 To the upper end of one of these bolts the lower end of a connecting rod 30 is pivotally secured, the upper end of said connecting rod being pivoted to the angular extension 32 formed on the lower end of an indicator arm 31. This arm is vertically disposed and is formed at the juncture of the extension 32 therewith, with a sleeve 33 which is rotatably disposed upon a bolt 34 which is threaded at one end in a bar 35

35 rigidly fixed upon the face of a vertically disposed plate 36. The upper end of the arm 31 is provided with a lead receiving tube 37, and to said arm one end of a leaf spring 38 is rigidly fixed, the free end of said spring being adapted to engage the stick of lead and normally hold the same in engagement with the surface of a chart indicated at 39 upon which the weight indications are recorded in the operation of the

50 machine.

The vertically disposed substantially parallel rods 40 are pivotally connected at their lower ends to the other of the bolts 29 carried by the rods 28, said rods 40 extending 55 above the top of the frame 5 upon opposite sides of the vertical wall 6 thereof. The upper ends of these rods are guided in the upper eyes 42 which are formed upon the upper ends of the vertical bars 41, said bars being 60 rigidly fixed at their lower ends to the horizontal bar 35. It will be observed that the rear face of the bar 35 is spaced from the face of the plate 36 so as to permit of the passage of the chart paper therebetween, 65 said bar serving as a guide for the paper

and acting to retain the same closely upon the face of said plate. The chart paper is preferably arranged upon a roll indicated at 43 and mounted in the rear of the plate 36. The upper end of the plate 39 is 70 slightly curved as shown at 39' so as to allow the paper to pass smoothly thereover and obviate liability of tearing the same.

The upper ends of the rods 40 are angularly disposed as indicated at 40' and 75 threaded to receive the nuts 44. To these threaded ends of said rods the sections 45 of a jointed marker are connected, said sections being pivotally connected to the pairs of similar sections 46 which are adjustably 80 connected by the short rods 47. The inner elements 46 of each pair are also pivotally connected, and in said ends and concentric to the pivot a stick of lead is arranged. A leaf spring 48 is secured to one of the elements of the marker and bears at its free end against the lead to hold the same in contact with the surface of the chart as described in connection with the indicating arms 31.

90 In order to continuously move the paper chart in the passage of the material through the machine, I provide the rollers 49 which are rotatably mounted in the supporting legs or standards 50 upon which the plate 36 is mounted. To one of the roller shafts, a worm gear 51 is secured, and said gear meshes with the teeth of a worm 52 formed upon a shaft 53 which is mounted in suitable bearings arranged on the frame 5. A 100 sprocket 54 is rigidly fixed upon the end of the shaft 53 and is traversed by an endless chain 55 which passes around a similar sprocket on the drive shaft 27. The other ends of the rollers are provided with the 105 intermeshing pinions 56 so that said rollers are at all times positively rotated at the same speed.

110 In the use of my improved mechanism, the chart paper is passed over the front face of the plate 36 and behind the bar 35, and inserted between the opposed engaged surface portions of the rollers 49. As power is imparted to the cylinder shaft 14 through the medium of the chain 26 connecting said 115 shaft with the drive shaft, the wheat or other grain products is admitted to the hopper 22 from whence it is deposited through the conveying tube 21 into the peripheral grooves or pockets 17' which are 120 provided in the receiving cylinder 17. The weight of the material as it strikes the periphery of the cylinder overcomes the counter-balance weight 19 and causes the end of the shaft 14 carrying the cylinder to lower, 125 the cylinder and its case of course moving therewith. Thus the rod 28 will be elevated, thereby forcing the rod 30 upwardly and oscillating the indicator arm 31 upon its pivot to move the pencil point carried thereby 130

upon the face of the chart and inscribe said chart whereby the weight of the material entering the machine is recorded. It will be understood that the material flows in a continuous stream while at the same time the receiving cylinder is being rotated and constantly discharging the material after it is weighed from the drum or case. This drum or case is of course provided with a suitable discharge spout or mouth at its bottom. It will be seen, however, that the transmission of power to the shaft 14 does not in any manner affect the accurate balance of said shaft and the receiving drum as the connection of the drive chain to the shaft is located directly beneath the pivot shaft 10. At the same time that the material is weighed, the paper chart moves over the surface of the plate 36 and as it is drawn beneath the pencil point carried by the indicator arm, the line which is inscribed thereon will indicate the weight of such material, said paper chart being suitably marked and provided with designating characteristics. The weighing mechanism on one side of the recorder may receive the raw material while that on the other side receives the flour which is the product of such material.

For the greater convenience of the user and in order to simplify so far as possible the labor involved in keeping an accurate account or record of the capacity of the mill, the intermediate marking device is employed; and it will be seen that as this device is connected to the vertical rods 40, the movement of which is controlled by the separate weighing mechanisms, the entire quantity of material passing through both of such mechanisms may be readily determined. This intermediate recording device is for the purpose of indicating the number of pounds of the particular grade of material which is necessary to produce a barrel of flour, the intermediate portion of the chart being suitably marked off in accordance with any well known system for keeping such records.

In addition to the above I also provide means for automatically operating an electric alarm bell when the material is fed to the machine too fast. This means consists of a contact member 57 which is arranged upon the upper end of each of the bars 41. To this contact, the positive wire 58 of an electric circuit is connected. The negative wire 58' of said circuit is connected to the lower end of the arm 31 which is suitably insulated from the pivot bolt 34 and from the rod 30. The electric battery is diagrammatically illustrated at 59 and the alarm bell is similarly illustrated at 60. It will thus be seen that when there is an excessive movement of the indicator arm 31 toward the upright bars 41, they will strike the con-

tacts 57 and connect the electrical circuit so as to ring the bell and thus indicate to the operator that the material is not feeding properly to the cylinder.

From the foregoing it is believed that the construction and operation of my improved weighing and recording mechanism will be fully understood.

While I have described the invention as particularly adapted for use in connection with a grain mill, it will be obvious that the device may also be used for weighing other materials than grain. The invention is, however, peculiarly adapted for the former purpose in that it will record the quantity of the raw material entering the mill and also of the product of such material so that the percentage of offal may be accurately gaged. The capacity of the mill in barrels is also automatically estimated. The device is, moreover, comparatively simple in its construction, positive in its operation and is not liable to get out of order so that a minimum amount of care and attention on the part of the operator is required.

While I have shown and described the preferred form and construction of the various parts, it will be understood that the invention is susceptible of considerable modification without departing from the essential feature or sacrificing any of the advantages thereof.

Having thus described the invention what is claimed is:—

1. In a mechanism of the character described, the combination of a rod fulcrumed intermediate of its ends, bearings arranged on said rod on opposite sides of its fulcrum, a shaft rotatably mounted in said bearings, a cylinder fixed on one end of said shaft, a casing for said cylinder, a counterbalancing weight for said cylinder arranged on one end of said rod, means for feeding a continuous stream of material to the cylinder to overbalance the cylinder, driving means connected to said shaft in line with the fulcrum of said rod to continuously rotate said cylinder, and means automatically actuated in the movement of the cylinder under the weight of material thereon to record the weight of said material.

2. In a mechanism of the character described, the combination of a rod fulcrumed intermediate of its ends, a casing fixed to one end of said rod, a counterbalancing weight on the other end of the rod, bearings arranged on said rod on opposite sides of its fulcrum, a shaft rotatably mounted in said bearings and extending into the casing, a material receiving cylinder arranged within the casing and fixed on said shaft, means for feeding a continuous stream of material to the cylinder, means for continuously rotating said cylinder to discharge the material, and means automatically actuated in the

bodily movement of said cylinder by the weight of the material thereon to record the weight of said material.

3. In a mechanism of the character described, the combination of a shaft having a material receiving cylinder on one end, a pivotally mounted counter-balanced rod disposed in parallel relation to said cylinder shaft, said rod carrying bearings for the shaft, a casing for the cylinder, the journal of said counter-balanced rod being secured to the cylinder casing, a drive shaft, an endless flexible connection connecting said cylinder shaft immediately beneath the journal of the counter-balanced rod with said drive shaft, and means connected to said counter-balanced rod and automatically actuated by the weight of the material on said cylinder to record the weight of such material.
- 20 4. In a mechanism of the character described, the combination of a material receiving cylinder mounted for bodily oscillatory movement, a casing therefor, means for feeding a continuous stream of material to said cylinder, means for rotating said cylinder, a vertically disposed plate, a chart movable over the face of said plate, means for continuously moving said chart in the rotation of the cylinder, and a marker arranged for movement over the face of said chart and automatically actuated in the bodily movement of the cylinder to record the weight of material deposited thereon upon said chart.
- 35 5. In a mechanism of the character described, the combination with a pair of counterbalanced material receiving cylinders, of a chart, means for feeding a continuously moving stream of material to each of said cylinders, means automatically actuated in the bodily movement of the cylinders under the weight of the material thereon to record upon said chart the combined weight of the material deposited on said cylinders, and 45 additional means independently actuated in the movement of each of said cylinders to

separately record the amount of material deposited upon each cylinder.

6. In a mechanism of the character described, the combination with a pair of counter-balanced material receiving members, of a chart, indicator arms movable over the face of the chart, a marker carried by each of the arms, rods connecting said arms with the material receiving members whereby said markers are automatically moved in the movement of said members under the weight of material thereon to record the weight of the material deposited in each of said members, vertically movable parallel rods connected to each of said members and actuated thereby, and a jointed marking element connecting the upper ends of said rods and actuated by the same, substantially as and for the purpose set forth.

7. In a mechanism of the character described, the combination with a counter-balanced cylinder provided with grooves in its periphery to receive material, a casing therefor, means for feeding the material to said cylinder in a continuous stream, means for rotating said cylinder, of a paper roll, a vertically disposed plate adjacent to the roll, means for continuously moving the paper upon the face of said plate, a guide bar for said paper mounted on the plate, markers mounted on said guide bar, connections between said markers and the counter-balanced cylinder whereby said markers are moved as the material is fed to the cylinder, and an additional marker separately connected to each of said cylinders and independently actuated in the bodily movement thereof to inscribe upon the paper a record of the passage of the material over both of said cylinders.

In testimony whereof I hereunto affix my signature in the presence of two witnesses.

GUY F. HOOVER.
